CIRCUIT BREAKER

William H. Stuellein, East McKeesport, Walter S. Hawkins, Wilkinsburg, and Gayne D. Gamel, Verona, Pa., assignors to Westinghouse Electric Corporation, East Pittsburgh, Pa., a corporation of Pennsylvania

Application August 22, 1946, Serial No. 692,338

17 Claims. (Cl. 200—88)

1

This invention relates to circuit breakers and more particularly, to circuit breakers of the type that are automatically operated instantaneously on heavy overload currents above a predetermined magnitude, and after a time delay on persistent overload currents of lesser magnitude.

One object of the invention is to provide a circuit breaker with an improved trip device which will automatically trip the breaker instantaneously in response to heavy overload currents above a predetermined value, after a relatively short time delay in response to overload currents in an intermediate range below said predetermined value and after a relatively long time delay in response to persistent overload currents of relatively low value.

Another object of the invention is to provide a circuit breaker with an improved electroresponsive trip mechanism having an armature movable in one direction by a thermally responsive element to effect tripping of the breaker after a relatively long time delay, the armature being movable in another direction independently of the thermally responsive element and under the control of a mechanical escapement device to effect tripping of the breaker after a relatively short time delay and a second armature operable independently of the thermally responsive element and the mechanical escapement device to effect instantaneous tripping of the breaker.

Another object of the invention is to provide a circuit breaker with a novel trip mechanism embodying an electromagnet having a normally latched armature which is rotatable by a thermal element to effect unlatching of the armature and tripping of the breaker under certain circuit conditions the armature being operated under the control of a mechanical escapement device independently of said thermal element to trip the breaker under certain other circuit conditions and a second armature operable independently of the thermal element and the mechanical escapement to instantaneously trip the breaker.

Another object of the invention is to provide a circuit breaker with an improved trip mechanism of the character described in the preceding paragraphs which is of rugged construction and reliable in operation.

The novel features that are considered characteristic of the invention are set forth in particular in the appended claims. The invention itself, however, both as to structure and operation, together with additional objects and advantages thereof, will be best understood from the following detailed description of a single embodiment thereof when read in conjunction with the accompanying drawings, in which:

Fig. 1 is a vertical sectional view through the center pole of a circuit breaker embodying the features of the invention.

Fig. 2 is an enlarged vertical sectional view of

2

the trip mechanism, taken on line II—II of Fig. 3 and looking in the direction of the arrows.

Fig. 3 is a bottom view of the mechanism shown in Fig. 2, and

5 Fig. 4 is a horizontal sectional view taken on line IV—IV of Fig. 2 and looking in the direction of the arrows.

Referring to Figure 1 of the drawings, the circuit breaker is provided with an operating mechanism common to all of the poles which is mounted in a U-shaped main frame 16 having spaced sides 17 (only one being shown) rigidly connected by a cross member 19. The frame 16 is mounted on the central portion of a base 11 of insulating material and is secured thereto by means of bolts 21 and 23. The outer ends of the sides 17 of the frame are rigidly connected by a cross member 25.

The bolt 23 extends through the base and the cross member 19 and serves to rigidly secure a connector 27 of conducting material to the cross member and to the base 11. A shaft 29 extending through an opening in the connector 27 and through openings in the sides of the frame 16 pivotally supports a pair of spaced arms 31 (only one being shown) having their free ends integral with a contact arm 30 for the center pole. The contact arms 30 (Fig. 1) for the outer poles are identical with the arm 30 for the center pole but are not provided with arms 31. The contact arms for the outer poles are rigidly secured to a tie bar 67 which extends across all of the poles and which is clamped to the center pole contact arm 30 by means of a split clamp 70 and a screw 71. The three contact arms 30 are thus mechanically connected for movement together. Rectangular tubes 69 of insulating material between the tie bar 67 and contact arms 30 for the several poles serve to insulate the three movable contact arms and their associated contacts from the tie bar 67.

40 The movable contact structures and the stationary contacts for the several poles are alike and therefore only the center pole contact means has been shown. The contact arm 30 for the center pole pivotally carries a main movable contact member 47 and a movable arcing contact member 55. The main contact member 47 is pivoted on a pivot pin 49 supported in projections 51 of the contact arm 30, and the movable arcing contact member 55 is pivoted on a pivot pin 57 supported in projections 59 of the arm 30. The main movable contact member 47 carries a contact 33, and a contact 35 is secured to the arcing contact member 55. These contacts 33 and 35 are adapted to respectively engage fixed contacts 39 and 37 secured on a conductor 41 which is in turn secured to the base 11 by means of bolts 43. The conductor 41 extends upwardly and is bent at right angles, the bent portions extending through an opening in the base 11 to form a terminal connector 45.

55 A spring 53 compressed between a spring seat

on the contact arm 30 and a spring seat on the main contact member 47 provides contact pressure to the main contacts 33-39 when the contact arm is in the closed position. Contact pressure for the arcing contacts 35-37 is provided by a spring 63 surrounding a rod 61 pivotally connected to the arcing contact member 55 and slidably through an opening in a spring seat on the contact arm 30. The spring 63 is compressed between a washer 65 seated on a shoulder on the rod 61, and the spring seat on the contact arm 30. The rod 61 has a nut 75 on the outer end thereof which acts to limit counterclockwise rotation of the arcing contact member 55 about its pivot when the contact arm 30 is moved to open the contacts. Counterclockwise movement of the main contact member 47 is limited by a projection 73 thereon striking the body of the contact arm 30. The adjustment of the nut 75 on the rod 61 is such that the arcing contacts 35-37 open after the main contacts 33-39 open during an opening operation of the circuit breaker, and close before the main contacts close during a closing operation.

When the contact arm 30 is operated to open the contacts, the arc across the arcing contacts 35-37 resulting from the rupture of the current is drawn into an arc extinguisher indicated generally at 16 where the arc is cooled and extinguished. Any suitable arc extinguisher may be employed, the one illustrated comprising, generally, a stack of slotted plates (not shown) of magnetic material disposed adjacent the paths of travel of each of the arcing contacts 35. The plates serve to draw the arc towards the ends of the slots where it is broken up into a plurality of short arcs which are quickly cooled and extinguished.

The movable arcing contact member 55 is connected by a flexible shunt conductor 77 to the main contact member 47, and another flexible shunt conductor 79 connects the main contact member 47 to the connector 27. The connector 27 for the center pole is secured to the cross member 19 of the frame 16 by the bolts 23, and the connectors 27 for the outer poles (not shown) are bolted to the base 11 with a spacer (not shown) between the base and each of these connectors in order to align the members 27 of the outer poles with the corresponding member 27 for the center pole. A conductor 175, secured to a projection 177 of the connector 27 by means of a bolt 179 extends downwardly therefrom and is secured to the upper end of an energizing coil 167. The lower end of the coil 167 is secured to a conductor 185 which, in turn, is secured to a conductor 81. The conductor 81 is bent at right angles and extends through an opening in the base 11 where it forms a terminal connector 83 which, together with the terminal connector 45, serves to connect the pole of the breaker in an electrical circuit.

The electrical circuits for the several poles of the breaker are essentially the same. The circuit of each pole extends from the corresponding terminal connector 45 through the conductor 41, the main contacts 33-39, the main contact member 47, the flexible shunt conductor 79, the connector 27, conductor 175, coil 167, and the conductor 81 to the terminal connector 83. The circuit for the arcing contacts 37-35 extends from the terminal connector 45, through the conductor 41, the arcing contacts 37-35, contact member 55, the flexible shunt conductor 77, the main contact member 47, and through the previously described circuit to the terminal connector 83.

The contact arms 30 are biased in a clockwise or opening direction by means of a pair of springs 85 (only one being shown). These springs are tensioned between the center pole contact arm 30 and a fixed pivot 87 supported in the main frame 16. In the closed position of the breaker, the center pole contact arm 30 and consequently all of the contact arms are releasably restrained in closed contact position (Fig. 1) by means of a toggle and linkage mechanism which is collapsible to cause opening of the contacts. The toggle and linkage forms a part of the common operating mechanism.

This collapsible linkage includes a lever 89 pivotally mounted on a fixed pivot 91 supported on the main frame 16. The lever 89 comprises a pair of levers rigidly connected by an integral cross bar 117, and is operatively connected to the support arms 31 of the center pole contact arm 30 by a main operating toggle comprising toggle links 93 and 95. The toggle link 93 has one end pivoted on a pin 101 supported on the lever 89 and the link 95 is pivoted on a pivot pin 99 on the arms 31. The links 93 and 95 are pivotally connected by a knee pivot pin 97. The toggle link 95 comprises a pair of links rigidly connected by means of an integral cross bar 115.

The free end of the lever 89 is pivotally connected by means of a link 103 to one arm of a lever 105 pivoted on the fixed pivot 87. The other arm of the lever 105 is pivotally connected to a toggle link 107 of a tripping toggle comprising the link 107 and a toggle link 109. The link 109 is pivoted on a fixed pivot 113 supported on the frame 16, and comprises a pair of links joined near the pivot 113 by a yoke 123 provided with projections 125 and 127. The toggle link 107 comprises a pair of links connected by a yoke 119 having a bent portion to which is secured an extension 121 of insulating material. The toggle links 107 and 109 are pivotally connected by a knee pivot pin 111. The purpose of the extension 121 is to cooperate with a part connected to a manually operable handle 141 to manually trip the breaker in a manner to be more fully described later. The lever 105 and the link 103 each comprise a pair of members rigidly connected by yokes substantially as illustrated.

The linkage just described serves to releasably hold the contact assemblage including the movable contacts for all of the poles of the breaker in closed contact position. In the closed position, the main operating toggle 93-95 is overcenter above a line through the center of the pins 99-101, and a second toggle, one link of which comprises the overcenter links 93-95 and the other link of which comprises the lever 89, is overcenter above a line through the center of the pins 99 and 91. The overcenter movement of the main operating toggle 93-95 is limited by the projecting end of the link 93 engaging the cross bar 115 of the link 95.

With the main operating toggle 93-95 and the toggle comprising the links 93-95 and the lever 89 in the overcenter position, as shown in Fig. 1, the springs 85 bias the lever 89 in a clockwise direction. Clockwise movement of the lever 89, however, is normally prevented by the tripping toggle 107-109 which is overcenter to the left of a line through the center of the fixed pivot 113 and the point of connection of the toggle link 107 with the lever 105. The toggle 107-109 is biased to its overcenter position by a spring 128 tensioned between the yoke 119 and the fixed pivot 113. The overcenter position of the tripping

toggle 107-109 is adjustably determined by the projection 125 of the yoke 123 engaging an adjusting screw 129 in the cross member 25 of the frame. The tripping toggle 107-109 in its overcenter position, acting through the lever 105 and the link 103, prevents clockwise movement of the lever 89 and consequently holds the movable contact assemblage in the closed contact position against the biasing influence of the springs 85.

The tripping toggle 107-109 is adapted to be moved overcenter outwardly in a direction to cause its collapse to effect opening of the contacts by means of an overload trip device indicated generally at 133 (Fig. 1). The trip device is operable in response to overload currents in the circuits of the breaker to actuate a trip rod 135 and cause collapse of the tripping toggle 107-109. The trip rod 135 is slidably vertically through a shunt trip device 165. The shunt trip device forms an additional tripping means for tripping the breaker and is adapted to be energized from a suitable source, controlled from a remote point and in a manner well known in the art, to operate the trip rod and trip the breaker.

When operated either by the shunt trip device or by the overload trip device 133, the trip rod 135 is thrust upwardly and strikes the projection 127 of the yoke 123 and rocks the toggle link 109 clockwise about the fixed pivot 113. This movement of the link 109 causes collapse of the tripping toggle 107-109 permitting clockwise movement of the lever 89 which permits the springs 85 to rock the movable contact assemblage clockwise to open the contacts.

The main operating toggle 93-95 does not immediately collapse, but the force of the springs 85 applied through the contact arm 30-31 and the main operating toggle causes collapse of the toggle comprising the links 93-95 and the lever 89 which results in a clockwise movement of the lever 89. This movement is transmitted through the link 103 and the lever 105 to complete the collapse of the tripping toggle 107-109.

The clockwise or opening movement of the contact arm 30 is arrested by projections (not shown) thereon striking portions 137 of the frame 16. At this time the rebound of the inertia of the main operating toggle 93-95 and the parts of the linkage 89, 103 and 105 starts the main operating toggle overcenter in a direction to cause its collapse. By the time the knee pin 97 of the toggle has passed overcenter below the line 99-101 the weight of the parts acts to complete the collapse of the toggle 93-95 and causes the linkage 89, 103, 105 and the tripping toggle 107-109 to be automatically reset to their normal positions. The main operating toggle 93-95 remains in collapsed condition until the contacts are closed.

The contacts are closed manually by operation of the previously mentioned handle 141. The handle is rotatably mounted in a bracket 143 of insulating material secured to the outer end of the main frame 16. Operatively connected to the mechanism (not shown) operated by the handle, is a link 151. The lower end of the link 151 is recessed and straddles a pulley-shaped projection 153 rigidly secured on a cross member 147 rigidly connecting the outer ends of a pair of spaced contact closing levers 145. These levers are disposed on the outside of the frame 16 and are pivotally supported on the ends of the fixed pivot 91 which project beyond the sides of the frame. The inner ends of the levers 145 are rigidly connected by a cross member 149. Spaced

projections 152 extending from the center portion of the cross member 149 support a pivot pin 157 upon which is rotatably mounted a roller 155.

The contacts are closed manually by clockwise rotation of the handle 141. This movement of the handle, through connections (not shown) thrusts the link 151 downwardly and due to its engagement with the projection 153, rotates the closing lever 145 in a clockwise direction. During this movement of the lever 145, the roller 155 engages the link 93 of the now collapsed main operating toggle 93-95 and moves this toggle to its overcenter position. Since at this time the tripping toggle 107-109 has been restored to its overcenter position, rotation of the lever 89 is prevented and consequently the force applied by the roller 155 to straighten the toggle 93-95 rotates the contact arm 30 counterclockwise to close the contacts and to tension the springs 85.

The clockwise movement of the closing lever 145 moves the toggle 93-95 overcenter above the line 99-101 so that the contacts are held in the closed position until the breaker is again tripped.

Upon release of the handle 141 following a contact closing operation, a spring 159 tensioned between the closing lever 145 and the frame 16 restores the lever 145 in a counterclockwise direction. This movement of the lever 145 and the projection 153 thrusts the link 151 upwardly to restore the handle 141 to its neutral position.

The circuit breaker may be tripped manually by rotation of the handle 141 through a small angle in a counterclockwise direction from its neutral position. When the handle is rotated in tripping direction, a projection (not shown) on the link 151 engages the extension 121 on the yoke 119 of the toggle link 107 and rocks the link counterclockwise about its point of connection with the lever 105. This moves the tripping toggle 107-109 overcenter in a direction to cause its collapse and effects opening of the contacts in the previously described manner.

The construction of the circuit breaker as thus far described is substantially the same as that fully disclosed in Patent No. 2,337,565, issued December 28, 1943, to John W. May, and assigned to the assignee of the instant application.

As previously stated, the trip rod 135 is operated to effect tripping of the breaker by means of a current responsive trip device 133. There is a trip device 133 provided for at least two of the poles of the breaker but since the trip devices are alike only the one for the center pole will be described.

Referring to Fig. 2 of the drawing, each of the trip units comprises an electromagnetic trip means indicated generally at 161, a mechanical escapement device indicated generally at 163 and a shunt tripping electromagnet 165. The electromagnetic trip means 161 comprises the energizing coil 167, a fixed core member 169, a time delay tripping armature 171 and an instantaneous tripping armature 173. The upper turn of the energizing coil 167 is mechanically and electrically secured to the short conductor 175 which is similarly secured to the projection 177 of the connector 27 and to the base 11 by means of a bolt 179, a spacer 181 of insulating material being provided to space the parts away from the base. The lower end of the energizing coil 167 is connected by means of a rivet 183 to the short conductor 185 which is secured to the terminal connector 83. The lower end of the fixed core member 169 is provided with feet 186 which are secured by

means of bolts 187 to the conductor 83, and the conductor 83 is secured to the base 11 of the breaker by means of bolts 188. The upper end of the fixed core member 169 is divided and straddles the projection 177 and the conductor 175, each portion being suitably secured to the spacer 181 one on each side of the conductor 175 thus insulating the upper end of the fixed core member from the conductor.

The time delay tripping armature 171 (Fig. 2) is generally cylindrical and is disposed within the energizing coil 167 for rotation and also for longitudinal movement. A flanked member 189 is rigidly secured by means of screws 191 to the lower end of the armature 171. A rod 193 integral with the flanked member 189 extends downwardly and has a sleeve 195 threadedly engaging the lower end thereof. The sleeve 195 fits within an opening in the bottom of a cup-shaped member 197 having a flange 199 integral with the upper end thereof by which the member 197 is adjustably secured by means of screws 201 (Fig. 3) to the lower leg of the fixed core member 169. The flange 199 is provided with concentric slots 203 engaging the screws 201 to permit rotatable adjustment of the member 197 relative to the fixed core member 169 and relative to the armature 171 for a purpose to be hereinafter described.

Disposed in the cup-shaped member 197 is a cylindrical latch member 205 having an annular groove 207 therein into which extend opposing studs 209 (Fig. 3) carried on the legs of a U-shaped arm 211. The bight of the arm 211 is secured by any suitable means, as by welding, to the bight of a second U-shaped arm 213 having its two arms pivoted on pivot pins 215 supported in the two legs of a U-shaped bracket 217. The bight of the U-shaped bracket 217 is secured by means of screws 219 to a cover 221 rigidly supported on the spacer 181 on the base 11. The downwardly extending arms 213 between them support a bar 223 provided with trunnions 225 for pivotally engaging openings in the arms 213. An adjusting screw 227 rotatably supported in the bar 223 threadedly engages a block 229 (Figs. 2 and 4) having spring studs 231 extending horizontally from each side thereof. Springs 233 having their lower ends hooked over the spring studs 231 and their upper ends hooked over spring studs 235 projecting inwardly from the side members of the bracket 217, serve to bias the lever 211-213 in a counterclockwise direction and thus bias the latch member 205 downwardly against the bottom of the member 197.

Mounted on the rod 193 for rotation therewith is a latch 237 disposed below and in latching engagement with the latching portion 239 of the latch member 205 to thereby latch the armature 171 in its unlatched position. In order to mount the latch 237 on the rod 193 for rotation therewith, a substantially square opening is provided in the latch 237 which engages a substantially square portion of the rod 193. A spring 241 (Fig. 2) compressed between the latch 237 and a shoulder on the sleeve 195 biases the latch 237 against the latch member 205 and a spring 243 compressed between the latch 237 and the member 189 biases the latch 237 in the opposite direction. The purpose of the springs 241 and 243 is to prevent rattle of the latch 237 which is slidably longitudinally on the rod 193 between the end of the sleeve 195 and the shoulder on the rod.

The armature 171 is rotated about its axis to unlatch itself from the latch member 205 by a helical bimetal element 245 having its lower end secured to the energizing coil 167 by means of the rivet 183. The upper end of the bimetal element 245 is secured to a guide cup 247 rotatably mounted on the flanged inner end of a short tubular shaft 249 supported in the upper leg of the fixed core member 169. The shaft 249 is secured in place by means of a nut 251. The armature 171 is provided with a longitudinally extending slot 253 which cooperates with a lug 255 secured to the upper end of the helical bimetal element 245. The lug 255 serves to rotate the armature 171 and the latch 237 relative to the latch member 205 to effect unlatching of the armature 171 and the slot 253 permits tripping movement of the armature after it is unlatched.

The instantaneous trip armature 173 is disposed in an opening in the armature 171 and is biased against the member 189 by means of a spring 257 coiled about the armature 173 and compressed between the shouldered upper end of the armature 171 and a flange on the lower end of the armature 173. The armature 173 is tubular and is secured to a rod 259 having a shouldered upper end upon which is disposed a washer 261. A guide sleeve 263 surrounding the rod 259 and disposed between the armature 173 and the washer 261 has a sliding fit in the tubular shaft 249. A flanged nut 265 is threaded onto the end of the rod 259. A lever 267 is pivotally mounted on a pin 269 supported in the two arms of a U-shaped bracket 271 which is secured to the upper leg of the fixed core 169. One end of the lever 267 is bifurcated and straddles the rod 259 between the washer 261 and the flanged nut 265. As will hereinafter be described upward movement of either of the armatures 171 or 173 rocks the lever 267 clockwise to effect tripping of the breaker.

When the lever 267 for any pole of the breaker is operated it acts through a trip bar 273 and the mechanical escapement device 163 to actuate the trip rod 135 to trip the breaker. The trip bar 273 is rotatably mounted in spaced arms 275 projecting from a frame 277. The frame 277 is rigidly secured to the lower leg of a U-shaped core member 279 for the shunt trip magnet 165 and supports an integral housing 280 in which the mechanical escapement is mounted. The upper leg of the core member 279 is rigidly secured to formed portions 281 (Fig. 1) of the side member 17 of the main frame 16. The shunt trip magnet 165 is provided with an energizing coil 283 and a movable armature 285 which normally rests on a stop 287 supported in the side walls of the housing 280. The armature 285 is attached to a tube 289 surrounding the trip rod 135. The shunt trip coil 283 may be energized from any suitable source, and, when energized, moves the armature 285 and the tube 289 upwardly to strike the projection 127 (Fig. 1) and trip the breaker in the previously described manner.

A U-shaped member 291 (Figs. 2 and 3) mounted on the lower end of the trip rod 135 embraces a pin 293 carried between a pair of spaced plates 295 which are pivotally mounted on a pin 297 supported in the side walls of the housing 280. The plates 295 are provided with shoulders 299 which are biased by means of a spring 301 against a pin 303 mounted in a pair of spaced arms 305 also pivotally-supported on the pin 297. One end of the spring 301 is at-

tached to a pin 307 supported between the plates 295 and the other end of the spring is hooked through an opening in a portion of the housing 280. The spaced arms 305 are operatively related to one arm 308 of a lever 309 secured by means of a screw 311 to the trip bar 273 for rotation therewith. A pair of springs 313 disposed one on each side of the lower end of the lever 309 surround spring guides 315 having one end pivotally mounted on a pin 317 projecting from both sides of the arm 308. The other ends of the spring guides are provided with longitudinal slots 319 embracing the pin 303. The other arm 321 of the lever 309 is disposed to be engaged by the rounded head 323 of an adjusting screw 325 threaded into the lever 267 and locked in adjusted position by means of a lock nut 327.

The mechanical escapement time delay device 163 (Figs. 2 and 3) comprises an escapement wheel 329 and an inertia member 331. The wheel 329 is rotatably mounted on a shaft 333 supported in the side walls of the housing 280 and the inertia member 331 is mounted for oscillation on a pin 335 supported in the two arms of a U-shaped lever 337 which is pivotally supported on the shaft 333. Between them the arms 305 support a pin 339 upon which is mounted a roller 341 which engages a slot 343 in the escapement wheel 329 thus operatively relating the escapement device to the trip mechanism.

The trip device 133 provides for tripping the breaker in response to overload currents in three ranges after a time delay commensurate with each range of overload currents. The time delays are herein defined as "long time delay," "short time delay" and "instantaneous" tripping. The ranges of overload current may be arbitrarily defined as low range up to fifteen times normal rated current; intermediate range between fifteen and thirty times normal rated current; and instantaneous tripping thirty times normal rated current or over, or short circuit.

The operation of the trip device, assuming the occurrence of an overload current in the low range, is described as follows: when the coil 167 is energized in response to a persistent overload in the low range the armature 171 is attracted upwardly in a direction to effect tripping of the breaker. It will be remembered that the armature is latched by means of the latch members 205 and 237 to the lever 211-213 which is restrained in the position shown in Fig. 2 by the springs 233. The energization of the electromagnet in response to overload currents in the low range is insufficient to overcome the tension of the springs 233, consequently, the armature 171 does not immediately move upwardly. If the overload persists, however, the bimetal helix 245 becomes heated and, since the lower end of the bimetal is secured to a fixed member, the upper end carrying the lug 255 rotates about the axis of the rod 259. The upper end of the bimetal helix is secured to the guide cup 247 and to the lug 255, consequently, the guide cup 247 will rotate with the upper end of the helix 245 and, since the lug 255 engages the slot 253 in the armature 171, the armature will also rotate with the upper end of the bimetal helix. Since the flanged member 189 is secured to the armature 171, this member together with the latch 237 will rotate therewith relative to the latch member 205 which is prevented from rotating by means of longitudinal projection 345 (Fig. 4) on the member 197 engaging in longitudinal slots in the latch member 205. After the armature 171 has been rotated, a predetermined

distance by the bimetal helix 245 the latch 237 is brought into alignment with an opening 347 in the latch member 335 and is unlatched therefrom, whereupon the armature 171 is moved upwardly in tripping direction by the already energized electromagnet. As the armature 171 moves upwardly, it moves the instantaneous tripping armature 173 and the rod 259 therewith and rotates the lever 267 clockwise about its pivot 269. As the lever 267 rotates, the head 323 of the screw 325 engages the arm 321 of the lever 309 and attempts to rotate this lever in a counterclockwise direction. The energization of the electromagnetic trip device 161 in response to overload currents in the low range is insufficient to compress the springs 313, consequently the force applied to the lever 309 is transmitted through the springs 313 to rotate the arms 305 in a counterclockwise direction and, due to the engagement of the pin 303 with the shoulders 299 on the plates 295, rotates the plates also in a counterclockwise direction. The rotation of the arms 305 and of the plates 295 is retarded by the escapement device 163. Due to the pin and slot connection 341-343 the counterclockwise rotation of the arms 305 applies a force to rotate the escapement wheel 329 in a clockwise direction. The escapement wheel 329 is provided with teeth 349 about a portion of its periphery which engage, and, upon clockwise rotation of the wheel 329, cause oscillation of the inertia member 331 to retard the rotation of the escapement wheel 329 and of the arms 305. This provides a short time delay in addition to the time delay occasioned by the heating and rotation of the bimetal helix to unlatch the armature 171. As soon as the last tooth 349 escapes the inertia member 331, the arms 305 are free to continue their tripping movement unretarded. The armature 171 thereafter functions through the lever 267, lever 309, springs 313 and the plates 295 to thrust the trip rod 135 upwardly to operate the tripping toggle 107-109 and effect opening of the breaker contacts in the previously described manner.

After the breaker contacts are opened and the coil 167 is deenergized, the armature 171 is restored to the position shown in Fig. 2 by the force of gravity, moving the lever 267 to its normal position and lowering the latch 237 to its position below the latch portion 239 (Fig. 4) of the latch members 205. Thereafter, as the bimetal helix cools, the armature 171 and the latch 237 are rotated to reenergize the latch 237 with the latch 205 in latching position.

The spring 301 (Fig. 2) is provided to restore the plates 295, trip rod 135, arms 305 and the escapement wheel 329 to their respective normal positions as shown in Fig. 2. The spring 301, acting through the shoulders 299 of the plates 295 and the springs 313, also move the lever 309 to its operative position.

Upon the occurrence of an overload current within the intermediate range of overload currents, that is, between fifteen and thirty times the normal rated current, the coil 167 is energized sufficiently to move the armature 171 upwardly against the tension of springs 233 without unlatching it from the lever 211-213. Shortly after the start of the upward movement of the armature, the head 323 of the screw 325 engages the arm 321 and operates the lever 309 to compress the springs 313. The energization of the electromagnetic trip device 161 in response to overload currents in the intermediate range of overload currents is sufficient to compress the springs 313 but does not immediately effect trip-

ping of the breaker. When the springs 313 are compressed, they apply a force to the arms 305 moving these arms and the plates 295 in tripping direction. This movement is retarded by the action of the mechanical escapement device 163. However, since the mechanical escapement 163 provides the sole time delay on intermediate overloads, this time delay is relatively short, and tripping will be effected as soon as the wheel 329 escapes from the inertia member 331.

When an overload current above thirty times rated current, or a short circuit, occurs the electromagnetic trip device 161 operates to instantaneously actuate lever 267 and effect instantaneous tripping of the breaker. Under this condition the armature 171 is immediately moved upwardly independently of the armature 171 and the springs 233. Also, the tripping electromagnet, when energized in response to overload currents above thirty times normal, overcomes the springs 313 (Figs. 2 and 3) and operates the trip rod 135 directly and independently of the mechanical escapement device to instantaneously trip the breaker. During such an operation the lever 309 is rocked counterclockwise with sufficient force to compress the springs 313, the guides 315 sliding over the pin 303 without moving the arms 305. A nose 351 on the arm 308 of the lever 309 engages the spaced plates 295 and moves these plates counterclockwise to thrust the trip rod 135 upwardly and trip the breaker in the previously described manner. The instantaneous tripping action occurs at high speed and the mechanical time delay device does not have time to function.

Following an instantaneous tripping operation the lever 309 and the trip bar 273 are restored to their unoperated positions by the expansion of the springs 313 and the spring 301 serves to restore the plates 295 and the trip rod 135 to their normal positions. The armature 171 is restored to normal position by the spring 257.

Means are provided for adjusting the trip device in order to vary the amount of time delay on both long time delay tripping and short time delay tripping. The adjusting means for the long time delay device comprises the member 197 in which the latch member 205 is slidably supported. It will be remembered that the member 197 is provided with a flange 199 having concentric slots 203 therein through which the screws 201 extend to secure the member 197 to the fixed core member 169. By loosening the screws 201, the member 197 may be rotated in either direction from the position in which it appears in Fig. 3. Rotation of the member 197 (Fig. 4) through the projections 345 which engage the longitudinal grooves in the latch member 205, the latch member is rotated relative to the latch 237. This varies the amount of deflection required of the bimetal helix 245 before the armature 171 is unlatched and actuated to trip the breaker.

Indicating means is provided to indicate the setting of the member 197. The indicating means comprises an indicating wheel 353 (Figs. 2 and 3) mounted on a vertically disposed shaft 355 supported for rotation in ears 357 formed inwardly from the bracket 217. A cotter pin 359 extending through an opening in the upper end of the shaft 355 above the upper ear 357 supports the shaft and wheel 353 in position. The wheel 353 is provided with teeth about a portion of its periphery which mesh with teeth on the flange 199 so that when the member 197 is rotatably adjusted the wheel 353 is also rotated. The edge

of the wheel 353 is visible through a sight opening in a name plate 361 suitably secured to the bracket 217 and bears indicia designating the setting of the adjusting device.

The amount of time delay provided by the mechanical escapement device 163 may be varied by moving the inertia member 331 relative to the escapement wheel 329. Referring to Fig. 2, it may be seen that the wheel 329 is provided with teeth about a portion only of its periphery. Movement of the inertia member 331 circumferentially relative to the escapement wheel 329 varies the number of teeth which must actuate the inertia member before the wheel 329 escapes therefrom and permits operation of the trip rod 135 to trip the breaker. Threadedly engaging the connecting portion of the U-shaped lever 337 which supports the inertia member 331 is a screw 363 which also engages in one of a series of openings 365 in the portion of the housing 280 which is concentric with the shaft 333. To adjust the inertia member, the screw 363 is removed and the lever 337 is rotated in either direction to the desired position. The screw 363 is then reinserted to retain the lever 337 and the inertia device 331 in the selected position. In order to obtain a fine adjustment of the escapement device there is provided a stud 367 which threadedly engages the housing 280 and is locked in position by means of a lock nut 369. The upper end of the stud 367 is disposed in the path of the roller 341 and thereby acts as a limit stop for the escapement wheel 329. By loosening the lock nut 369 the stud 367 may be screwed in and out thereby varying the position of the wheel 329 relative to the inertia member 331.

It was previously set forth that, in response to overload currents in the intermediate range of overloads, the armature 171 is operated to trip the breaker without unlatching it from the springs 233. In order to operate in this manner the current value must be high enough to overcome the tension of the springs 233, that is, a minimum of fifteen times normal rated current. The minimum overload current required to operate the armature 171 without unlatching may be varied by varying the tension of the springs 233. This is accomplished by turning the screw 227 (Fig. 2) thus moving the block 229 to which the lower ends of the springs 233 are attached to increase or decrease the tension of the springs.

It will be understood that the limits of the intermediate range of overload currents (fifteen to thirty times normal) are merely by way of example, and these may be varied as will be readily understood by those skilled in the art to which the invention appertains.

Having described the invention in accordance with the patent statutes, it is to be understood that various changes and modifications may be made therein without departing from some of the essential features of the invention. It is, therefore, desired that the language of the appended claims be given as reasonably broad interpretation as the prior art permits.

We claim as our invention:

1. In a circuit breaker comprising relatively movable contacts, trip means operable to effect opening of said contacts, said trip means comprising an electromagnet having an armature movable in one direction to trip the breaker, latch means for latching said armature against tripping movement, thermally responsive means operable when heated a predetermined amount in response to overload currents to rotate said

armature to unlatch said armature, and means operated by said armature to cause tripping of said breaker.

2. In a circuit breaker comprising relatively movable contacts, trip means operable in response to overload currents to effect opening of said contacts comprising electroresponsive means including an armature movable longitudinally to cause tripping of the breaker, means releasably restraining said armature against tripping movement, and thermally responsive means operable when heated a predetermined amount to rotate said armature to effect release of said armature from said restraining means and thereby permit longitudinal tripping movement of said armature.

3. In a circuit breaker comprising relatively movable contacts, trip means operable in response to overload currents to effect opening of said contacts comprising electroresponsive means including an armature movable axially to cause tripping of the breaker, means releasably restraining said armature against tripping movement, and thermally responsive means comprising a bimetallic helix operable when heated a predetermined amount to rotate said armature to effect release of said armature from said restraining means and thereby permit tripping movement of said armature.

4. In a circuit breaker comprising relatively movable contact means, trip means operable in response to overload currents to effect opening of said contact means comprising a solenoid having a core member movable longitudinally to effect tripping of said breaker, means releasably restraining said core member against tripping movement, thermally responsive means operable when heated a predetermined amount to rotate said core member to cause release of said core member from said restraining means.

5. In a circuit breaker comprising relatively movable contact means, trip means operable in response to overload currents to effect opening of said contact means comprising a solenoid having a core member movable longitudinally to effect tripping of said breaker, means releasably restraining said core member against tripping movement, thermally responsive means comprising a bimetal helix operable when heated a predetermined amount to rotate said core member to cause release of said core member from said restraining means.

6. In a circuit breaker comprising relatively movable contact means, trip means operable in response to overload currents to cause opening of said contact means comprising electroresponsive means including an armature movable in one direction to cause tripping of the breaker, means releasably restraining said armature against tripping movement, thermally responsive means for rotating said armature to effect release of said armature from said restraining means, and means for adjusting said restraining means relative to said armature to vary the releasing time of said armature.

7. In a circuit breaker comprising relatively movable contact means, trip means operable in response to overload currents to effect opening of said contact means comprising a solenoid having a core member movable in one direction to cause tripping of the breaker, means releasably restraining said core member against tripping movement, thermally responsive means operable when heated to rotate said core member to cause release of said core member from said restraining means, and means for adjusting said restraining

means relative to said core member to vary the amount of rotation required to effect release of said core member.

8. In a circuit breaker comprising relatively movable contact means, trip means operable in response to overload currents to effect opening of said contact means comprising a solenoid having a core member movable in one direction to cause tripping of the breaker, means releasably restraining said core member against tripping movement, thermally responsive means comprising a bimetal helix operable when heated to rotate said core member to cause release of said core member from said restraining means, and means for adjusting said restraining means relative to said core member to vary the amount of rotation required to effect release of said core member.

9. In a circuit breaker comprising relatively movable contact means, a trip device operable in response to overload currents to cause opening of said contact means comprising an energizing winding, a first armature movable axially to trip the breaker, means normally restraining said first armature against tripping movement, time delay means comprising a bimetal helix operable when heated in response to overload currents below a predetermined value to rotate said first armature to release said armature and effect tripping of the breaker after a time delay, and a second armature operable in response to overload currents above said predetermined value to instantaneously trip the breaker independently of said first armature.

10. In a circuit breaker comprising relatively movable contact means, a trip device operable in response to overload currents to cause opening of said contact means comprising an energizing winding, a first armature movable axially to trip the breaker, means normally restraining said first armature against tripping movement, time delay means comprising a bimetal helix operable when heated in response to overload currents below a predetermined value to rotate said first armature to release said armature and effect tripping of the breaker after a time delay, means for adjusting said restraining means relative to said first armature to vary the amount of time delay, and a second armature operable in response to overload currents above said predetermined value to instantaneously trip the breaker independently of said first armature.

11. In a circuit breaker comprising relatively movable contact means, a trip device operable in response to overload currents to cause opening of said contact means comprising an energizing winding, a first armature movable axially to trip the breaker, biased means normally restraining said first armature against tripping movement, a first time delay means comprising a bimetal helix operable when heated in response to overload currents below a predetermined value to rotate said first armature to release said armature and effect tripping of the breaker after a time delay, said biased means at times permitting axial tripping movement of said armature independently of said first time delay means, a second time delay means for retarding tripping movement of said first armature when said armature is moved independently of said first time delay means, and a second armature operable in response to overload currents above said predetermined value to instantaneously trip the breaker independently of said first armature.

12. In a circuit breaker comprising relatively movable contact means, a trip device operable in

response to overload currents to cause opening of said contact means comprising an energizing winding, a first armature movable longitudinally to trip the breaker, biased means normally restraining said first armature against tripping movement, a first time delay means comprising a bimetal helix operable when heated in response to overload currents below a predetermined value to rotate said first armature to release said armature and effect tripping of the breaker after a relatively long time delay, said biased means permitting longitudinal movement of said armature independently of said first time delay means, a second time delay means for retarding tripping movement of said first armature with a relatively short time delay when said armature is moved independently of said first time delay means, means for adjusting said restraining means relative to said first armature to vary the amount of time delay provided by said first time delay means, and a second armature operable in response to overload currents above said predetermined value to instantaneously trip the breaker independently of said first armature.

13. In a circuit breaker comprising relatively movable contact means, trip means operable in response to overload currents to effect automatic opening of said contact means comprising an energizing winding, an armature movable axially to trip the breaker, biased means releasably restraining said armature against tripping movement, a first time delay means comprising a bimetal element operable when heated in response to overload currents to release said armature to effect tripping of the breaker after a time delay, means for adjusting said restraining means relative to said armature to vary the amount of time delay provided by said first time delay means, said biased means at times permitting axial movement of said armature independently of said first time delay means, a second time delay means for retarding tripping movement of said armature when said armature is moved independently of said first time delay means, and means for adjusting said second time delay means to vary the amount of time delay provided thereby.

14. In a circuit breaker comprising relatively movable contact means, trip means operable in response to overload currents to effect automatic opening of said contact means comprising an energizing winding, an armature movable axially to trip the breaker, means releasably restraining said armature against tripping movement, a first time delay means comprising a bimetal element operable when heated in response to overload currents to release said armature to effect tripping of the breaker after a time delay, means biasing said restraining means to permit tripping movement of said armature independently of said first time delay means, means for adjusting said restraining means relative to said armature to vary the amount of time delay provided by said first time delay means, a second time delay means comprising a mechanical escapement mechanism for retarding tripping movement of said armature when said armature is moved independently of said first time delay means, and means for adjusting said second time delay means to vary the amount of time delay provided thereby.

15. In a circuit breaker comprising relatively movable contact means, trip means operable in response to overload currents to cause automatic opening of said contact means comprising an en-

ergizing winding, an armature movable axially to trip said breaker, means releasably restraining said armature against tripping movement, a first time delay means comprising a thermal element operable to rotate said armature to cause release of said armature, means permitting movement of said armature in tripping direction independently of said first time delay means, and a second time delay means for retarding tripping movement of said armature when said armature is moved in tripping direction independently of said first time delay means.

16. In a circuit breaker comprising relatively movable contact means, trip means operable in response to overload currents to cause automatic opening of said contact means comprising an energizing winding, an armature movable axially to trip said breaker, means releasably restraining said armature against tripping movement, a first time delay means comprising a thermal element operable to rotate said armature to cause release of said armature, means permitting movement of said armature in tripping direction independently of said first time delay means, means opposing tripping movement of said armature independently of said first time delay means, means for adjusting said opposing means to vary the minimum overload required to move said armature independently of said first time delay means, and a second time delay means for retarding tripping movement of said armature when said armature is moved in tripping direction independently of said first time delay means.

17. In a circuit breaker comprising relatively movable contact means, a trip device operable in response to overload currents to cause automatic opening of said contact means comprising an energizing winding, a first armature movable axially to trip the breaker, means releasably restraining said first armature against tripping movement, a first time delay means comprising a bimetal helix operable when heated in response to overload currents below a predetermined value to rotate said first armature to effect release of said armature to thereby effect tripping of said breaker after a relatively long time delay, means permitting movement of said first armature in tripping direction independently of said first time delay means, a second time delay means for retarding tripping movement of said first armature with a relatively short time delay when said armature is moved independently of said first time delay means, and a second armature operable in response to overload currents above said predetermined value to instantaneously trip the breaker independently of both of said time delay means.
